(57) **CLAIM**

The ornamental design for an inverter housing, as shown and
described.

DESCRIPTION

FIG. 1 is a perspective view of an inverter housing showing
our new design;

FIG. 2 is front elevational view thereof;

FIG. 3 is rear elevational view thereof;

FIG. 4 is a left side elevational view thereof;

FIG. 5 is right side elevational view thereof;

FIG. 6 is a top plan view thereof; and,

FIG. 7 is a bottom plan view thereof.

The broken line portion of the figure drawings is included to
show unclaimed subject matter only and forms no part of the
claimed designs.
